United States Patent Office

Des. 196,779
Patented Nov. 5, 1963

196,779

TANK UNIT

Robert W. Forsyth and John P. Forsyth, Burbank, Calif.,
assignors to Lockheed Aircraft Corporation, Burbank,
Calif.

Filed Jan. 28, 1963, Ser. No. 73,325

Term of patent 14 years

(Cl. D14—3)

FIG. 1

FIG. 3

FIG. 5

FIG. 6

FIGURE 1 is a perspective view of a tank unit, showing our new design;

FIG. 2 is a side elevational view thereof;

FIG. 3 is a top plan view thereof;

FIG. 4 is a front elevational view of the front portion of the tank unit;

FIG. 5 is a sectional view taken on lines 5—5 of FIG. 2;

FIG. 6 is a sectional view taken on lines 6—6 of FIG. 2;

FIG. 7 is a rear elevational view of the rear portion of the tank unit.

The dominant features of our design reside in those portions shown in full lines.

We claim:

The ornamental design for a tank unit, as shown and described.
